UNITED STATES PATENT OFFICE

2,475,300

SWITCH AND CIRCUIT BREAKER

Edmond F. Webb, Franklin Village, Mich., assignor to Chrysler Corporation, Highland Park, Mich., a corporation of Delaware

Application July 23, 1945, Serial No. 606,526

7 Claims. (Cl. 200—113)

1

This invention relates to an improved switch and circuit breaker for an electrical system.

An object of the invention is the provision of a combination switch and circuit breaker for controlling energization of a plurality of electrical circuits from a common source of energy, and to provide such a device operable to effect concurrent energization of said circuits and to accommodate deenergization of one of the latter circuits while maintaining another thereof energized.

A further object of the invention is the provision of a device of this character operable as above to control electrical circuits having respectively different overload values, and to provide a device which at its control is responsive to individual circuit overload values irrespective of the overload values of other circuits of the electrical system which may be concurrently energized.

A further object of the invention is the provision in an electrical system including a plurality of circuits adapted to be energized from a source of energy through a switch including parts movable together to a position for concurrently energizing respective circuits and relatively movable when so positioned by a predetermined temperature induced in the respective circuits to deenergize one thereof independently of another, and to provide a switch in which the aforesaid parts are bimetallic.

Other objects and advantages of the invention will be more apparent from the following description taken in connection with the accompanying drawing, in which:

Fig. 1 is a sectional side elevational view through a device embodying the invention.

Fig. 2 is a top plan view of the Fig. 1 device.

Fig. 3 is a top plan view of the movable switch member included in Figs. 1 and 2.

Fig. 4 is a side elevational view of the movable switch member.

Fig. 5 is a view of a wiring diagram embodying the invention.

Fig. 6 is a view similar to Figs. 3 and 4 but showing a modified form of movable switch member.

The combination switch and circuit breaker is adapted to control a plurality of electrical circuits which may be energized from a common source of energy, for example, a storage battery. In many instances the devices fed by these circuits may draw relatively different current values during operation and frequently two or more of such devices may be concurrently operated as in the case of the head lamps and tail lamps of a motor vehicle. As illustrated, the switch and circuit breaker

2

breaker include a casing 10 in which is fixed a multi-layer plate 11 of insulating material and carrying a plurality of terminals 12 provided with contacts 13. A plug 14 having a central bore 15 is fixed to the base of the casing 10 and is adapted to be threaded into a suitable support not shown. An actuating rod 16 extends through the bore 15 into the housing 10 and has a plurality of arms 16' non-rotatably fixed thereto. Each arm 16' has an upturned end which is engaged in a recess in a multiple layer plate 17 for rotation of the latter in response to rotation of the rod 16. A coil spring 18 yieldably urges the plate 17 upwardly.

15 Disposed between the plates 11 and 17 is a switch, generally designated by the numeral 19, including a central body having a plurality of downwardly extending legs 20 for supporting the switch on the plate 17. A plurality of arms 21 extend outwardly from the central body and each has a downwardly projecting leg 22 received in an opening 23 of the plate 17, as typified in Fig. 2. Each such arm carries a contact 24 adapted to engage with a certain contact 13 of a terminal 12 as will be more fully set forth.

20 The member 19 is of unitary bimetallic construction and may be formed by stamping the same from sheet stock including metallic layers 25, 26 having different coefficients of expansion and adapted to react to a predetermined temperature value, the layers being relatively arranged so that in thus reacting the arms 21 are moved downwardly as viewed in Fig. 1. The member thus acts as a circuit breaker by deenergizing a circuit when the current drawn therefrom exceeds a predetermined value. Where the devices to be energized by the respective circuits draw relatively different amounts of current, the aforesaid reactive temperature value of the arms is set 25 above the temperature induced in that circuit from which the greater amount of current is normally drawn.

25 The member 19 is depressed centrally at the central inlet contact 24 and when assembled as shown in Fig. 1, this centrally depressed portion is urged upwardly under the influence of the spring 18 to bring the central contact 24 into engagement with an associated contact (not shown) and to give a predetermined pressure at the outlet contacts 24 of the arms 21.

30 Referring to Fig. 5, the wiring diagram shows an electrical system including a plurality of circuits energized through the switch and circuit breaker 19 from a common source of energy such as a storage battery 28. As applied to a motor

vehicle the system includes a head lamp circuit 28 and a parking light circuit 30, the contacts 18 of which are selectively engaged by the contact of one arm 21, a tail light circuit 31, the contact 18 of which is engaged by a contact of another arm 21, and an auxiliary circuit 32, the contact of which is engaged by the contact of another arm 21. The auxiliary circuit 32 may supply current to a plurality of devices, for example, a radio receiving set and a space heater fan and inasmuch as these devices may be concurrently operated with the tail lamp the contacts for the circuits 31, 32 are so elongated as to permit such concurrent operation. The conductor 33 communicates with the aforesaid circuits and the battery 28 and a conductor 34 leads from the battery to the switch 19. When the switch 19 is moved to bring either arm 21 controlling the circuits 30, 31 to the "off" position indicated at 35, all circuits except the auxiliary are deenergized.

In operation, the spring 18 acting on the plate 17 urges the member 19 upwardly to maintain the contacts in suitable conducting engagement and by oscillation of the rod 16 the member 19 can be oscillated to a selected position as illustrated in which the circuits 30, 31, 32 are concurrently energized. As is well known, the head lamps, as well as the devices in the auxiliary circuit, may draw an amount of current from the circuit thereof greater than that drawn by the tail and parking lights from their respective circuits and therefore an arm 21 will react only to a temperature value which is above that which will be induced in that circuit from which the greater load is normally drawn, in this instance the head lamp or auxiliary circuit. Should the circuit 31 be overloaded by shorting the same to an extent to draw therefrom an amount of current greater than that normally drawn from a concurrently energized circuit, then the arm 21 controlling such circuit will be heated to a reacting temperature to deenergize the overloaded circuit only and the other concurrently energized circuits will not be affected by such overloading.

In the modification shown in Fig. 6, the member 19' includes a plurality of individual arms 21' fixed together centrally for selective oscillation as a unit and adapted to be included in the associated structure in a manner similar to that of the member 19. The arms 19' are of bimetallic construction and are adapted to react to respectively different temperature values predetermined in accordance with the temperature induced in the controlled circuit by normal operation of the device in such circuit. With this construction each circuit has a predetermined unloading value independently of the unloading value of other circuits concurrently energized therewith.

Although but two specific embodiments of the invention have herein been shown and described, it will be understood that various changes in the size, shape, and arrangement of parts may be made without departing from the spirit of the invention.

I claim:

1. In an electrical system including a plurality of circuits each having a contact, a switch member for controlling energization of said circuits including a plurality of arms centrally connected and otherwise spaced apart each having a contact, said switch member being movable between a first position to respectively engage a plurality of said arm contacts with said circuit contacts thereby to concurrently energize a plurality of

said circuits and a second position to deenergize said circuits, each of said arms constituting a bimetallic thermostat deflectible to disengage its contact from its engaged circuit contact when the load on the circuit of the latter contact exceeds a predetermined value while maintaining engaged the contacts of that circuit concurrently energized, each arm being capable of inherent deflection to restore engagement of such contacts independently of movement of said member between said positions.

2. In an electrical system including a plurality of circuits adapted to be energized from a common source of energy and each having a terminal, a switch member including a central body and a plurality of arms radiating therefrom in spaced relation and free for deflection relative to said body at the arm periphery remote from said body each having a contact, said member being movable between a plurality of positions for controlling energization of said circuits, including one position to respectively engage a plurality of said arm contacts with certain of said terminals thereby to concurrently energize a plurality of circuits, each of said plurality of arms being so thermostatically deflectible as to disengage the contact thereof from the engaged terminal independently of another arm when the load on the circuit having the last mentioned terminal exceeds a predetermined value while maintaining said member in its said one position.

3. In an electrical system including a plurality of circuits each having a terminal, a combination switch and circuit breaker for controlling energization of said circuits from a common source of energy including a plurality of individually formed arms each carrying a contact, means securing said arms together for unitary movement to so position certain of the same as to respectively engage the contacts thereof with certain of said terminals to thereby concurrently energize the circuits of the last mentioned terminals, each of said arms being of bimetallic construction and reactive to a respectively different predetermined temperature value to deflect in one direction to so move its contact as to deenergize the associated circuit independently of another of said concurrently energized circuits when said reactive predetermined value thereof is exceeded, and to deflect in another direction to so move its contact as to restore the circuit deenergized.

4. In a combination switch and circuit breaker for controlling operation of a plurality of electrically energizable devices each adapted to operate on current of a predetermined value, a bimetallic thermostat including individual parts, means securing said parts together for unitary movement to a position to respectively effect concurrent energization of at least two of said devices, said parts having relatively different temperature responsive characteristics for deflection one relative to the other to deenergize one of the last mentioned devices when the current supplied thereto exceeds said predetermined value.

5. In a combination switch and circuit breaker for controlling operation of a plurality of electrically energizable devices each adapted to operate on current of respectively different predetermined values, a bimetallic thermostat including individual parts adapted to react to respectively different predetermined values, means securing said parts together for unitary rotary movement to a position to respectively effect con-

current energization of at least two of said devices and for opposite deflection one relative to the other when in said position to respectively deenergize one of the last mentioned devices when the current supplied thereto exceeds said predetermined value and to energize the device so deenergized.

6. In an electrical system including a plurality of circuits adapted to be energized from a common source of energy and each having a terminal, a switch member including a central body and a plurality of arms radiating therefrom in relatively circumferentially spaced relation, each arm having a contact, means connected with said central body for rotating said member between a plurality of positions for controlling energization of said circuits, including one position to respectively engage a plurality of said arm contacts with certain of said terminals thereby to concurrently energize a plurality of circuits, each of said plurality of arms being so thermostatically deflectible as to disengage the contact thereof from the engaged terminal independently of another arm when the load on the circuit having the last mentioned terminal exceeds a predetermined value while maintaining said member in its said one position.

7. A combination switch and circuit breaker for controlling a plurality of electrical circuits

each having a terminal, said switch including a plurality of individual arms each having a contact, means connecting said arms together for unitary movement between a plurality of positions for controlling energization of said circuits including one position to respectively engage a plurality of said arm contacts with certain of said terminals thereby to concurrently energize a plurality of circuits, each of said plurality of arms being so thermostatically deflectible as to disengage the contact thereof from the engaged terminal when the load on the circuit of such engaged terminal exceeds a predetermined value while maintaining another of said arms in its said one position with the contact thereof engaged with its said certain terminal.
